ATTORNEY

UNITED STATES PATENT OFFICE.

BERTRAM J. KIFFE, OF MANKATO, MINNESOTA.

PHONOGRAPHIC RECORD AND TABLE.

1,391,637.

Specification of Letters Patent. Patented Sept. 20, 1921.

Application filed May 15, 1920. Serial No. 381,604.

To all whom it may concern:

Be it known that I, BERTRAM J. KIFFE, a citizen of the United States, residing at Mankato, in the county of Blue Earth and 5 State of Minnesota, have invented new and useful Improvements in Phonographic Records and Tables, of which the following is a specification.

This invention relates to a phonographic 10 record and table therefor, the principal object of the invention being to provide means for facilitating the removal of the record from the table.

Another object of the invention is to render it unnecessary to touch that part of the record which contains recording grooves and making the record easy to handle.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a face view of a record constructed in accordance with my invention.

Fig. 2 is a face view of the improved turn table.

Fig. 3 is a sectional view taken through 35 the improved turn table, with the improved record thereon.

In these views, 1 indicates the record which is of the usual disk type and is provided with the central hole 2, to receive the 40 spindle 3 of the graphophone which projects above the turn table 4. In carrying out my invention I form a pair of holes 5 in the record, one on each side of hole 2

and spaced a sufficient distance apart so as to permit insertion of the thumb and fore- 45 finger of one hand.

In order to permit the thumb and finger to enter these holes when the record is on the turn table I provide a cup shaped recess 6 in the center of the table. This will 50 space the bottom of the table from the record so as to permit the fingers to enter the openings or holes in said record, as clearly shown in Fig. 3.

It will thus be seen that the record can 55 be easily placed on the table and removed therefrom and without touching the grooved part of the record. The records can be easily handled without danger of dropping them, as will be apparent. 60

It is thought from the foregoing description that the advantages and novel features of my invention will be readily apparent.

I desire it to be understood that I may make changes in the construction and in 65 the combination and arrangement of the several parts, provided that such changes fall within the scope of the appended claims.

What I claim is:—

1. A record for graphophones having a 70 pair of finger receiving holes adjacent its center.

2. A disk record for graphophones having a pair of openings formed therein, one 75 on each side of the spindle receiving hole and spaced apart a distance to receive the finger and thumb of one hand.

3. A phonograph turn table having a recess formed at its upper face adjacent the 80 center thereof and a record for engaging the table, said record having a finger hole formed therein adjacent the center thereof.

In testimony whereof I affix my signature.

BERTRAM J. KIFFE.
